GEORGE WESTINGHOUSE, JR., OF PITTSBURG, PENNSYLVANIA.

LOCOMOTIVE-DRIVER BRAKE.

SPECIFICATION forming part of Letters Patent No. 373,706, dated November 22, 1887.

Application filed August 30, 1887. Serial No. 218,243. (No model.)

To all whom it may concern:

Be it known that I, GEORGE WESTINGHOUSE, Jr., residing at Pittsburg, in the county of Allegheny and State of Pennsylvania, a citizen 5 of the United States, have invented or discovered a certain new and useful Improvement in Locomotive-Driver Brakes, of which improvement the following is a specification.

My invention is designed more particularly 10 for use upon locomotive-engines of the "consolidation" type, or those having four pairs of coupled driving-wheels, but is likewise applicable in other constructions in which the application of braking power to two or more 15 pairs of wheels may be desired; and its object is to provide an apparatus of simple and inexpensive structure which shall be readily adaptable to engines of any of the ordinary patterns, and in the operation of which equal 20 pressure will be exerted upon each of the driving-wheels and equal wear correspondingly induced upon the tires thereof and the 25 brake-shoes.

To this end my invention, generally stated, 30 consists in the combination, with a pair of brake-heads suspended between two adjacent wheels, of brake-levers coupled between their ends to the brake-heads and coupled at one 35 end to a fixed support and to a brake rod, respectively, and a pressure-rod interposed between the ends of the brake-levers opposite those connected to the support and brake-rod.

The improvement claimed is hereinafter fully set forth.

35 In the accompanying drawings, Figure 1 is a side view in elevation of a portion of the frame and driving-wheels of a locomotive-engine, illustrating the application of a brake mechanism embodying my invention; Fig. 2, 40 a similar view on an enlarged scale; Fig. 3, a plan view, partly in section, of a portion of the mechanism; Figs. 4, 5, and 6, transverse sections through the frame, looking to the right, at the lines *x*, *y*, and *z*, respectively, of Fig. 45 1; Fig. 7, a view in perspective of one of the brake-rod-connecting arms detached; Fig. 8, a horizontal section, on an enlarged scale, through a pair of brake-levers and brake-heads; Fig. 9, a rear view, and Fig. 10 a side 50 view, of a brake-head.

In the instance herein exemplified my in-

vention is illustrated as applied in a locomotive-engine having four pairs of driving-wheels, 1 2 3 4, the axle-journals of which are mounted in boxes in the usual manner in the 55 frame 5. The brake mechanism of the wheels on one side of the engine corresponds in construction and operation with that of the other, and hence that of the left side, which is shown, need only be described. Brake-heads 6^a, 6^b which may be of any preferred type, are suspended in pairs by links or hanger 7 from the frame 5 between the driving-wheels 1 2 of the first and second axles and between the driving-wheels 3 4 of the third and fourth 65 axles, a brake-head being thus provided for each wheel, and the brake-heads being located in position for their shoes to be applied to the tires on alternately opposite sides of the respective driving axles. Each of the forwardly-facing brake-heads 6^a is, when, as in this case, the brake-cylinder is located at the rear of the engine, coupled by a pin, 8^a, to a 70 brake-lever, 9^a, at a point between the ends of said lever, and each of the oppositely-facing 75 brake-heads 6^b is similarly coupled by a pin, 8^b, to a brake-lever, 9^b. Each of the brake-levers 9^a is pivoted at its inner end by a fulcrum-pin, 10^a, to a bearing or support, 11, bolted to the frame, and the inner end of 80 each of the brake-levers 9^b is coupled to the forward end of one of a pair or series of 85 brake-rod sections, 12, the brake-lever 9^b farthest from the brake-cylinder being directly connected to the brake-rod section by a coupling-pin, 10, and the remaining brake 90 lever or levers 9 being each coupled through the intermediation of a brake-rod-connecting arm, 13, having a pin in its upper end fitting a hole in the lever 9. The rear brake-rod section 12 is coupled to the connecting arm 13 near the center of the latter, and the brake-rod section in advance thereof is coupled at its rear end to the lower end of the connecting 95 arm 13 and at its forward end to the lever 9^a of the next succeeding rearwardly-facing 100 brake-head 6 by the coupling pin 10 above specified. If the mechanism should be adapted to six pairs of wheels, the additional brake-rod section, which would in such case be required on each side, would be coupled at its rear end to the lower end of one connecting-

arm and at its forward end to the middle portion of a similar arm.

The power applied in setting and releasing the brakes is transmitted from one to the other 5 of the members of each pair of brake-levers 9 and 9^a by a pressure-rod, 19, interposed between and bearing at its ends against the outer ends of the brake-levers and fitted to rock or swivel therein in accordance with the movements of said levers about the axes of the pins 8 and 10^a, respectively. For this purpose the pressure- rods 19 are provided at each end with a spherical or ball bearing, 20, which fits a corresponding socket in the adjacent brake-lever 9 or 9^a, and is made adjustable upon the rod 19 to enable lost motion to be taken up from time to time as required. The bearings 20 are internally threaded to engage corresponding threads upon the pressure- rods 19, and are provided with squared projections on their inner ends, by which they may be rotated to vary their positions upon the pressure-rod. The brake-levers 9 and 9^a are of equal length, and the distance from the centers of 25 the sockets of the bearings 20 to the centers of the pins by which they are coupled to the brake-heads and to the fixed fulcrum and brake-rod section are equal or proportioned to give the desired force on each wheel.

30 3c. A brake-cylinder, 14, fitted with proper appliances for the admission and exhaust of fluid under pressure, is secured in any convenient position to the rear portion of the frame 5, and is provided with a properly-packed piston, the rod 15 of which is coupled by a link, 16, to the upper arm of a lever, 17, mounted in a bearing, 18, on the frame. The lower arm of the lever 17 is coupled to the rear brake-rod section 12, so that outward movement of the 40 piston-rod 15 will produce a corresponding backward movement of the brake-rod sections 12. The sections 12 are preferably formed in two parts connected by swivel-nuts 21, having right and left hand threads, to enable the length 45 of the sections to be readily adjusted as required; or any other suitable device for this purpose may be employed.

50 In operation the application of the brakes is effected by the admission of fluid-pressure to the brake-cylinder 14, which pressure, being transmitted through the piston-rod 15, link 16, and lever 17 to the rear brake-rod section 12, imparts rearward movement to the latter, such movement being through 55 the connecting-arm 13 imparted to the inner end of the rear brake-lever 9 and the forward brake-rod section 12, and through the latter to the inner end of the forward brake-lever 9. The brake-levers 9 then pivoting upon the 60 pins 8 as fulcrum, the pressure of the brake-rod sections 12 is exerted through the pressure- rods 19 upon the brake-levers 9^a, which turn upon the fulcrum-pins 10^a, and apply the shoes of the brake-heads 6^a to the wheels 1 and 3. When the latter are brought to a 65 bearing, the fulcrum of the brake-levers 9 are, through the pressure- rods 19, shifted from

their pins 8 to their bearings 20, and the levers 9, turning thereon, apply the shoes of the brake-heads 6 to the wheels 2 and 4. A 70 similar but reversed action is produced in releasing the brake, the forward movement of the brake-rod sections 12 in such case turning the brake-levers 9 upon the bearings 20 and relieving the shoes of the brake-head 6 from 75 their bearing on the wheels 1 and 2. The pressure which has theretofore acted through the pressure rods 19 upon the levers 9^a and brake-heads 6^a being consequently released therefrom, the gravity of the brake-heads 6^a 80 withdraws their shoes from the wheels 1 and 3, and during their withdrawal the pressure- rods 19, bearing upon the outer ends of the levers 9, cause the latter to turn upon the pins 8 and maintain the outer ends of the levers 9^a and 9 in normal relative position for a 85 succeeding operation.

It will be seen that while one of each pair of adjacent brake-heads is actuated by a brake-lever having a fixed fulcrum and the other by 90 a lever having a floating and shifting fulcrum the leverage is under all conditions equal in both, or may readily be proportioned as desired, and when equal the shoes will be applied with equal force to their respective 95 wheels. Each lever is of the second order, and the fulcrum of the levers are in the application of the brakes located at opposite ends thereof, respectively; but in each the power-arm is equal to the distance from the center 100 of the bearing 20 to the center of the pin at the opposite end of the lever, and the resistance-arm is equal to the distance from the center of said end pin to the center of the pin by which the brake-head is coupled to the 105 lever, said distance respectively being, as before stated, equal in the two levers.

I claim herein as my invention—

1. In a brake mechanism, the combination of a brake-lever pivoted to a fixed fulcrum, a 110 brake-lever having a floating or movable fulcrum, brake-heads coupled to said levers, a brake-rod coupled to the lever having the floating fulcrum, and a pressure-rod interposed between and bearing against the brake-levers, substantially as set forth.

2. In a brake mechanism, the combination of a pair of brake-heads suspended between two adjacent wheels, a pair of brake-levers, each coupled between its ends to one of the 120 brake-heads, a fixed support or fulcrum coupled to one end of one of the brake-levers, a brake-rod coupled to the corresponding end of the other lever, and a pressure-rod interposed between and bearing against the opposite ends of the brake-levers, substantially as set forth.

3. In a brake mechanism, the combination of two pairs of brake-heads, each pair of which is suspended between two adjacent wheels, two 130 pairs of brake-levers, each member of which is coupled to one of said brake-heads, fixed supports or fulcrum, to each of which one member of each pair of brake-levers is coupled, a

brake-rod coupled to the piston-rod of a brake-cylinder, a connecting-arm coupling said brake-rod to the member of one pair of levers which is unconnected to a fixed fulcrum, a brake-rod coupling the connecting-arm with the corresponding member of the other pair of levers, and pressure-rods interposed between and bearing against the ends of the levers which are unconnected to the fulcrum and brake rods, substantially as set forth.

4. In a brake mechanism, the combination of a pair of brake-levers pivoted at their adjacent ends to a fixed fulcrum and a brake-rod, respectively, brake-heads, each coupled to one of said levers between its ends, and a pressure-rod having its ends fitted to swivel or pivot in the ends of the brake-levers opposite those connected to the fixed fulcrum and brake rod, substantially as set forth.

5. In a brake mechanism, the combination of a pair of brake-levers pivoted at their adjacent ends to a fixed fulcrum and a brake-rod, respectively, brake-heads, each coupled to

one of said levers between its ends, and a pressure-rod having spherical or ball bearings on its ends fitting sockets in the ends of the brake-levers opposite those connected to the fixed fulcrum and brake-rod, substantially as set forth.

6. In a brake mechanism, the combination of a pair of brake-levers pivoted at their adjacent ends to a fixed fulcrum and a brake-rod, respectively, brake-heads, each coupled to one of said levers between its ends, and a pressure-rod provided with spherical or ball bearings secured adjustably upon it adjacent to its ends, and fitting sockets in the ends of the brake-levers opposite those connected to the fixed fulcrum and brake-rod, substantially as set forth.

In testimony whereof I have hereunto set my hand.
